Application August 12, 1944, Serial No. 114,863

Term of patent 14 years

(Cl. D52—1)

To all whom it may concern:

Be it known that I, Eric S. Guttmann, a citizen
of the United States, residing at Huntington, in
the county of Cabell and State of West Virginia,
have invented a new, original, and ornamental
Design for a Calculator, of which the following is
a specification, reference being had to the accom-
panying drawing, forming part thereof.

In the drawing:

Figure 1 is a face view of a calculator embody-
ing my new design.

Fig. 2 is a diametrical cross-sectional view.

The design is characterized by the novel sym-
metrical arrangement of the indicia.

I claim:

The ornamental design for a calculator, sub-
stantially as shown.

ERIC S. GUTTMANN.
